E. CROUSE

DISPENSING RESERVOIR

Filed Dec. 27, 1923

Inventor

Emory Crouse.

By *H. J. Crouse* Attorney

UNITED STATES PATENT OFFICE.

EMORY CROUSE, OF WICHITA, KANSAS.

DISPENSING RESERVOIR.

Application filed December 27, 1921. Serial No. 524,903.

This invention relates to an apparatus used for dispensing liquid fuel in measured quantities, and has special reference to the specific arrangement of pipes used for introducing the liquid into the transparent vessel or reservoir used for measuring.

In order to more clearly describe my invention, I shall have reference to the accompanying drawing in which the single view 10 shows my improved transparent measuring reservoir.

Numeral 1 represents the top of a sheet iron casing which is used to support the transparent reservoir 2, and also to enclose 15 the valves and piping of my apparatus, which, however, is not shown in this drawing. Reservoir 2 is preferably a cylindrical glass vessel secured to a metal bottom, not shown, and provided with an ornamental 20 cap 3. The liquid fuel enters the reservoir through pipe 4 whose top is provided with a cap 5. Directly beneath the lower edge of cap 5 I provide a number of holes 6 through which the liquid leaves the pipe. In order 25 to prevent splashing of the liquid as it enters the reservoir through holes 6, and to cause the liquid to reach the bottom of the reservoir in a quite and orderly manner, I enclose the upper end of pipe 4 with an aluminum tube 7 whose inside diameter is considerably greater than the outside diameter 30 of pipe 4; this tube has the upper end closed as indicated by numeral 8, which closure is provided with a vent 9. Tube 7 is held 35 in place by means of a screw 10, which has screw threaded engagement with cap 5. An overflow pipe 11 is also provided.

From the above it will appear that I have provided means whereby the liquid will enter 40 the reservoir at the top, but in such a manner that it will present the appearance of entering near the bottom. The holes 6 in the top of supply pipe 4 are above the level of the top of the overflow pipe 11, and as the aluminum tube 7 has a vent 9, it is obvious that 45 no siphoning action can take place when the liquid in pipe 4 recedes, as it sometimes will. By my arrangement of pipes, the liquid will enter the reservoir quietly and without 50 the formation of violent waves, as is the case where it enters directly at the bottom through a pipe.

However, the main feature of my improvement is the delivery of the liquid to the 55 container at the top and above the top of

the overflow pipe 11. In constructions of this class, the top of the overflow pipe determines the level of the liquid in the container when the latter is full, and in order to secure the full benefit and advantage of 60 the invention, it is necessary that the opening or openings at the top of the inlet pipe 4, through which the liquid enters the container, shall be above the top of the overflow pipe 11, or at least as high as the top 65 of said overflow pipe, since the main object of the invention is to prevent the possibility of the escape of the liquid in the container through the inlet or filling pipe 4. Where a different construction is employed, that is, 70 where the liquid is delivered to the container at the bottom through a pipe whose upper end is at or near the bottom of the container or terminates at any point below the top of the overflow pipe, it is necessary to 75 use a check valve in the inlet pipe to prevent the return of the liquid to the source of supply after the force, as air pressure, which causes the liquid to enter the container, ceases to act. But it is found in 80 actual practice, or in the use of dispensers of this character, that where valves are employed for this purpose, it is impossible to prevent them from leaking, and to the extent that leaks occur, a part of the liquid 85 in the container is returned to the supply tank and there is a consequent loss to the customer or purchaser. In other words, if the container holds ten gallons, the top of the overflow pipe is so located as to retain 90 this amount therein, and for obvious reasons an excess is always delivered which is taken care of by the overflow pipe. But if the open end of the inlet or filling pipe is below the top of the overflow pipe, and 95 there is a leaky check valve in the inlet pipe, a part of the ten gallons which the customer should receive will leak back into the supply tank before the contents of the container can be lowered to the open end 100 of the inlet pipe, and the farther the delivery opening of the inlet pipe is below the top of the overflow pipe, the greater will be the loss to the customer, and if this opening is at the bottom of the container, 105 as is usual, the maximum loss of course will be the result. But if the delivery opening of the inlet pipe is above the top of the overflow pipe, there can be no possible loss of liquid from the container through the in- 110

let pipe whether or not there is a valve therein, and consequently there is no necessity for a check valve in this pipe.

Hence, the real object of the invention set forth in this application is to prevent loss to the customer by leakage from the container through the inlet pipe after the container is filled.

Having now described my invention, what I claim as my invention or discovery is:

- 10 1. In a liquid dispenser, the combination with a container having an overflow pipe terminating in the upper portion thereof, of a supply pipe extending upwardly into the 15 container, and having its outlet opening at least as high as the top of the overflow pipe, and a housing enclosing said supply pipe, said housing being opened at the bottom and having a vent opening in its top.
- 20 2. In combination, a reservoir adapted to contain a liquid, a supply pipe for conducting said liquid into said reservoir, said pipe extending upwardly to a point near the top of said reservoir, an opening near the top 25 of said pipe, and means for conducting the liquid downwardly, comprising a tubular member having its upper end closed, said tubular member enclosing said pipe, and a vent in the upper end of said tubular member.
- 30 3. In combination, a reservoir adapted to contain a liquid, a supply pipe for conducting said liquid into said reservoir, said pipe extending upwardly to a point near the top 35 of said reservoir, a cap on the upper end of said pipe, a plurality of holes in said pipe near the upper end thereof, a tubular member enclosing said pipe, said tubular member having its upper end closed and provided with a vent.
- 40 4. In combination, a reservoir adapted to contain a liquid, a supply pipe for conducting said liquid into said reservoir, an overflow pipe having its upper end open, said 45 supply pipe having its upper end closed and

extending above the level of the overflow pipe, a plurality of openings in the sides of the supply pipe above the level of the overflow pipe, a tubular member enclosing said supply pipe and having its upper end closed, a vent in the upper end of said tubular member, and means for securing it centrally on the supply pipe.

5. In liquid dispensing apparatus, the combination with a container having an overflow pipe, of means extending above the top of the overflow pipe for supplying liquid to the container, such means being vented to prevent the escape of liquid from the container therethrough.

6. In liquid dispensing apparatus, the combination with a container having an overflow pipe, of a conduit extending above the top of the overflow pipe for supplying liquid to the container, said conduit being vented to prevent the escape of liquid from the container therethrough.

7. In liquid dispensing apparatus, the combination of a container having an overflow pipe, of means located within the container and extending above the bottom thereof for delivering liquid thereto at a point at least as high as the top of the overflow pipe, said means extending downwardly toward the bottom of the container and being vented to prevent the escape of liquid from the container therethrough.

8. In liquid dispensing apparatus, the combination of a container having an overflow pipe, of means located within the container and extending above the bottom thereof for delivering liquid thereto at a point at least as high as the top of the overflow pipe, said means extending downwardly to a point near the bottom of the container and being vented to prevent the escape of liquid from the container therethrough.

In testimony whereof I affix my signature.
EMORY CROUSE.
